UNITED STATES PATENT OFFICE.

WILLIAM HENRY POTTER, OF CHICAGO, ILLINOIS, ASSIGNOR TO WESTERN ELECTRIC COMPANY, INCORPORATED, OF NEW YORK, N. Y., A CORPORATION OF NEW YORK.

COIL-WINDING MACHINE.

Application filed December 27, 1923. Serial No. 682,853.

This invention relates to coil winding machines, and more particularly to an improved machine for winding strand material on ring shaped objects, especially toroidal coils.

In the present type of toroidal coil winding machines a supply of winding material is wound on a bobbin which forms a part of, or is made integral with the winding ring or shuttle. By reversing the revolving direction of the shuttle, the winding material is then drawn from the bobbin and wound on the coil. This operation is continued until the coil is completely wound.

Due to the fact that the winding ring or shuttle of the above type of machines passes through the center of the coil as the same is being wound, the capacity of the bobbin is necessarily small and therefore only a relatively small amount of winding material can be stored thereon. For this reason the operation of the machine must be suspended at frequent intervals to permit rewinding of the bobbin.

An object of this invention is to eliminate the time required to wind and rewind the bobbin on the present type of toroidal coil winding machines and thereby increase their production.

Another object of this invention is to construct a toroidal coil winding machine having a removable bobbin or supply spool lying wholly within the shuttle.

A further object of this invention is to construct a toroidal coil winding machine in which the supply spool is stationary during the winding operation, said supply spool having a flyer revolvably mounted at one end thereof by means of which the winding material is drawn therefrom.

A still further object of this invention is to construct a coil winding machine with an improved tensioning device for taking up the slack in the winding material as the same is being drawn from the supply spool and wound on the coil.

Other objects and advantages of the present invention will more fully appear from the following description and will be particularly pointed out in the appended claims.

In the accompanying drawings,

Fig. 1 is a side elevation, partly in section of a winding machine made in accordance with the invention;

Fig. 2 is a front elevation of the mechanism shown in Fig. 1;

Fig. 3 is a fragmentary detail view of the removable bobbin, and

Fig. 4 is a detail sectional view taken on the line 4—4 of Fig. 1.

The frame of the machine embraces two similar constructed parallel side frame members 10 and 11 respectively, which are integrally or otherwise rigidly connected one to another at their lower ends by a cross frame member 12, which in turn is rigidly supported on a flat surface 13, such as the top of a table or bench. Journalled in lower arms 14 and 15 of the frame members 10 and 11 respectively, is a driving pinion 16 which may be driven by any suitable source of power, such as an electric motor 17 and hand wheel 18.

A winding ring or shuttle 19 comprising two separate ring shaped members 20 and 21 are rigidly connected to each other by screws 22. (Fig. 4). The member 20 of the shuttle is provided on its periphery with gear teeth 45 suitable to be engaged by the teeth of the driving pinion 16. An idler gear 24 is journalled in upper arms 25 and 26 of the frame members 10 and 11 respectively, said gear being similar in size and construction to the driving pinion 16. Journalled in the lower portion of the frame members 10 and 11 is an idler roller 27 which serves as a support and guide for the winding ring 19.

A bobbin 28 containing a supply of winding material 29 lies wholly within the shuttle 19, and is securely held in place by means of an outwardly projecting lug 30 formed on its end flange 31 fitting snugly in a groove 32 in the shuttle member 21. On the opposite end flange 33 of the bobbin 28 a plate constituting a flyer 34 is revolvably mounted, said plate having an eye or opening 35 through which the winding material 29 passes to a guide roller 36 which centralizes its delivery to a tension device 37, from which it is led over a distributing roller 38 to the object on which the material is to be wound, illustrated in the drawings as a coil 39.

To permit the bobbin 28 to be replaced when the supply of winding material has run out, there is an opening in the shuttle member 20, which is suitably covered when the

machine is in operation, as by a removable plate 40, Fig. 4.

A hinged section 49 is provided in the shuttle 19 to permit the opening thereof for the insertion or removal of the coil or object to be wound.

As the coil 39 is being wound with material supplied by the bobbin 28, it is firmly supported and held in position by a bracket 10 41 journaled on a stud 42 projecting through the top of the support 13. A gear 43 is also journaled on the stud 42 and is rigidly secured to the bracket 41 so that it is rotatable therewith. A stud 44 is revolvably 15 mounted in a bearing 46 and has keyed thereto a ratchet wheel 47 and a gear 48 which meshes with the gear 43. A suitable hand lever (not shown) is provided for indexing the ratchet wheel 47, first in one direction and then in the other so that the coil 20 may be oscillated in an arc of about 180 degrees as the winding material is applied thereon.

The mechanism above described and illustrated in the drawings is used for winding that type of toroidal coils which are composed of two or more separate and distinct sections, each section being wound separately. Other suitable mechanism may be 30 employed for revolving the coil uniformly in one direction when it is desired to apply the winding material thereon in well defined layers.

The pinion 16 is driven by any suitable 35 source of power, such as an electric motor 17, causing the shuttle 19 to revolve in a clockwise direction as shown by the arrows in Fig. 1. While the shuttle 19 is revolving, the winding material 29 is drawn from 40 the bobbin 28 through the eye 35 in the flier 34 and led over the guide roller 36 to the tensioning device 37, from which it passes through the distributing roller 38 to the coil 39.

45 It is apparent from an inspection of Fig. 1 that while the shuttle 19 is revolving, during the first half of each revolution starting from the position shown, the winding material is drawn from the bobbin faster than it is being wound on the coil, while during the other half of each revolution, the amount of material wound on the coil is more than is being drawn from the bobbin, thus causing first a slack and then a tightening up of the winding material. This condition is due to the fact that the coil 39 is not positioned at the center of the shuttle 19. To maintain a uniform tension of the winding material during the complete winding 50 operation, the spring pressed tensioning device 37 rotates back and forth in the arc 55, assuming the position shown to take up the slack in the material caused in the first half of each revolution and assuming the dotted position to prevent tightening up of the

winding material in the second half of each revolution.

What is claimed is:

1. In a machine for winding strand material around a ring shaped object, a shuttle, a bobbin carried thereby, and a rotatable member carried by said bobbin for guiding the strand material as it is withdrawn therefrom. 70

2. In a machine for winding strand material around a ring shaped object, a shuttle, a bobbin carried thereby, means for supporting said bobbin in a fixed position with respect to said shuttle, and a rotatable member carried at one end of said bobbin for guiding the strand material as it is withdrawn therefrom. 75 80

3. In a machine for winding strand material around a ring shaped object, a shuttle, a bobbin carried thereby, means for causing a relative movement between the object being wound and said shuttle whereby material is withdrawn from the bobbin and applied on the object being wound, and a rotatable member carried at one end of said bobbin for guiding the strand material as it is withdrawn therefrom. 85 90

4. In a machine for winding strand material around a ring shaped object, a shuttle, a bobbin carried thereby, means for supporting said bobbin in a fixed position with respect to said shuttle, means for causing a relative movement between the object being wound and said shuttle whereby material is withdrawn from the bobbin and applied on the object being wound, and a rotatable member carried at one end of said bobbin for guiding the material as it is withdrawn therefrom. 95 100

5. In a machine for winding strand material around a ring-shaped object, a revolving shuttle, a bobbin carried thereby, and a flier for withdrawing strand material from said bobbin. 105

6. In a machine for winding strand material around a ring-shaped object, a revolving shuttle, a removable bobbin carried thereby, and a flier carried by said shuttle for feeding strand material from said bobbin. 110 115

7. In a machine for winding strand material around a ring-shaped object, a revolving shuttle, a removable bobbin carried thereby, a flier carried by said shuttle for feeding strand material from said bobbin, and means for maintaining a uniform tension on said strand material during the winding operation. 120

8. In a machine for winding strand material around a ring-shaped object, a revolving shuttle, a removable bobbin lying wholly within said shuttle, a support for said ring-shaped object, and means for oscillating said support during the winding operation. 125

9. In a machine for winding strand ma-

terial around a ring-shaped object, a revolving shuttle, a removable bobbin lying wholly within said shuttle, means for passing the strand material from said bobbin to said object, a support for said ring-shaped object, and means for oscillating said support during the winding operation.

10. In a machine for winding toroidal coils, a revolving shuttle, a removable bobbin lying wholly within said shuttle, a flier revolvably mounted at one end of said bobbin, an opening in said flier through which the winding material is drawn, guiding means for said winding material, and means for maintaining a uniform tension in said winding material during the winding operation.

11. In a machine for winding toroidal coils, a revolving shuttle, a removable bobbin lying wholly within said shuttle, means for passing the winding material from said bobbin to said toroidal coil, and means for oscillating said coil during the winding operation so that said winding material may be evenly distributed thereon.

12. In a machine for winding strand material around a ring-shaped object, a revolving shuttle, and an arcuate shaped bobbin carried by said shuttle.

30 13. In a machine for winding strand material around a ring-shaped object, a revolv-

ing shuttle, and an arcuate shaped bobbin removably carried by said shuttle.

14. In a machine for winding strand material around a ring-shaped object, a revolving shuttle, an arcuate shaped bobbin lying wholly within said shuttle, and means for distributing the strand material on said ring-shaped object.

15. In a machine for winding toroidal coils, a revolving shuttle, an arcuate shaped bobbin lying wholly within said shuttle, a disk revolvably mounted at one end of said bobbin, an opening in said disk through which the winding material is drawn from said bobbin, and means for distributing said winding material on said toroidal coil.

16. In a machine for winding toroidal coils, a revolving shuttle, an arcuate shaped bobbin lying wholly within said shuttle, a disk revolvably mounted at one end of said bobbin, an opening in said disk through which the winding material is drawn from said bobbin, and tensioning means for said winding material, comprising a roller supported by a spring pressed arm pivoted within said shuttle.

In witness whereof, I hereunto subscribe my name this 18 day of December A. D., 1923.

WILLIAM HENRY POTTER.
